PAGE 2

Fig.4

Fig.5

FIG. 1 is a top perspective view of a flood light, showing my new design.

FIG. 2 is an elevation as seen from the opposite end of FIG. 1.

FIG. 3 is a top plan view thereof.

FIG. 4 is a bottom plan view thereof incorporating a translucent lens.

FIG. 5 is a bottom perspective view showing a modified form of the flood light shown in FIG. 1 wherein the lens is transparent.

I claim:
The ornamental design for a flood light, as shown and described.
